COMBINATION LOCK

Fred Burns, Footscray, Australia

Application September 10, 1936, Serial No. 100,084
In Australia June 23, 1936

16 Claims. (Cl. 70—302)

This invention has reference to an improved combination lock and has been devised to provide such a lock that will be applicable to safes, boxes, cash bags, doors and the like, the said lock being 5 compact and of small proportions so as to provide the necessary neatness of appearance when attached to hand bags.

The object of this invention is to provide a combination lock that will have single control by 10 means of providing one knob or handle, the manipulation of which is adapted to effect the dual function of operating the locking mechanism and also to provide the release of the catch or bolt associated with said lock to effect the 15 opening of a safe, bag or the like.

With the above object in view, this invention apprehends more specifically a combination lock having a knob, handle, dial or the like for manipulation purposes and which may be rotated in a 20 clockwise and anti-clockwise direction to effect a predetermined setting of locking elements in order to permit a bolt or catch to be moved by a further manipulation of the control dial or knob whereby the safe, door or bag may be 25 opened.

An important feature embodied in the invention consists in that the control knob or handle has associated therewith indication devices for 30 selecting the combination of the lock, the locking members of which are operatively connected with the knob or handle and the movable bolt or catch whereby, on the locking members being adjusted according to the predetermined setting thereof, the correct manipulation of the handle or knob 35 permits the said bolt or catch to be moved for the purposes herein described.

It is a further important feature of the invention that the locking mechanism comprises a plurality of spaced concentrically arranged locking elements adapted to be brought into a predetermined setting of registration to permit the catch or bolt associated therewith to be displaced from the locking position in order to open the article or the like to which the lock is attached.

It is a further important feature of the invention that the locking elements comprise a plurality of concentric collars or rings rotatably mounted in conjunction with the control knob or handle and the movable bolt or catch, the said collars or rings having means associated therewith whereby rotation impulses to the outer ring or collar are transmitted to the inner collars or rings according to the direction of rotation imparted by the handle or knob whereby by rotating the handle or knob in a clockwise or anti-clockwise di-

rection, the rings or collars are set to the predetermined release position in accordance with a dial setting from the knob or handle to permit the said bolt or catch to be operated and displaced from the locked position for the purposes 5 described.

It is a further important feature of the invention that the locking elements are slidably displaced on a rib or ledge on the base plate of the lock which has formed thereon teeth, pins or the like to seat in the locked position between the collars or locking elements whereby each locking element or collar has to be independently set to bring slots or openings in the locking elements into registration whereby the said elements may 10 be displaced from the locked position by means of the teeth engaging with the slots, and in displacing the locking elements, the bolt or catch is moved therewith.

A still further important feature of the invention is that in operating the lock described, the control handle or knob is rotated in an anti-clockwise and clockwise direction in sequence whereby each locking element or collar is rotated until it reaches a position when the slots therein 20 are in registration at which position a displacement of the control handle or knob or portion thereof permits either the locking elements to move past and out of engagement with the locking teeth or vice versa according to the design 25 to release the catch or bolt.

Other features of this invention will be described hereinafter with reference to the accompanying drawing in which:—

Figure 1 is a front elevation of the combination 35 lock as adapted to a safe door.

Figure 2 is a sectional plan view of Figure 1.

Figure 3 is a sectional elevation of the combination locking mechanism.

Figure 4 is an end elevation of the combination 40 locking mechanism with the base plate removed.

Figure 5 is an exploded perspective view of the combination lock.

According to one form of carrying my invention into practical effect, the improved lock may comprise a base plate 6 on which is formed an up-raised rib 7 extending to the periphery of said plate 6 from near the centre thereof. This rib 7 has formed thereon a plurality of teeth or pins 45

8. Adjacent the inner end of the rib 7 is a recess or slot 9 formed through the base plate 6 to permit said plate 6 to be moved at right angles to its axial centre line in order to permit unlocking mechanism to be operated as hereinafter de- 55

scribed, the said slot 9 also limiting the movement of said plate 6.

The slot 9 of the base plate 6 engages with a rectangular or other shaped projection 10 formed on the rear of a disc or circular plate 11 having a plurality of concentric recesses or grooves 12 formed on the front thereof and into which recesses are freely and independently disposed locking elements 13 comprising rings or collars.

10 A radial slot 14 is also formed through this circular plate 11 to receive the rib 7 on the base plate 6 so that the top of the teeth 8 formed in said rib 7 become flush with the front face of the circular plate 11 and the spaces 15 between said teeth

15 coincide with the circumferential grooves 12 in said circular plate 11 to permit the locking elements 13 to be rotated in their respective grooves 12 when the base plate 6 is disposed in the locking position.

20 A spindle 16 extends from the centre of the disc or circular plate 11 and is threaded at its upper end to receive a cap 17 and locking nut 18, the inner surface of the cap 17 having concentrically arranged thereon recesses or grooves 19 to correspond with the grooves 12 in the disc or circular plate 11 and fit over the upper circumferential edges of the locking elements 13 in a manner to permit said elements 13 to be rotated within their grooves 12 and 19.

25 30 Mounted to the disc or circular plate 11 is a flanged casing 20 which completely covers the locking elements 13 and retaining cap 17, the flange 21 of the casing engaging with a recess 22 in the circular plate 11 and being held in a removable manner by a nut 23, the periphery of said plate 11 being threaded for the purpose.

35 The flange 21 of the casing 20 is provided with a cut-out 24 through which the teeth 8 and rib 7 on the base plate 6 are permitted to pass when the locking elements 13 are disposed in an unlocked position.

40 Projecting inwardly from the interior wall of the flanged casing 20 and preferably near the flange 21 thereof is a projecting lug or pin 25 and for the purpose of assembly of the casing 20 and associated parts a slot 26 is provided in the retaining cap 17 and through which the pin 25 passes.

45 50 Each of the locking elements 13, as before mentioned, is capable of independent rotation and are arranged concentrically around each other and provided with lugs 27 projecting exteriorly and interiorly from the wall thereof and in the same plane as the lug 25 on the flanged casing 20. The respective lugs 27 on the locking elements 13 are adapted to engage with corresponding lugs 27 on the adjacent locking element 13, the engagement of the lugs 27 with each other causing the locking elements 13 to rotate in unison, that is to say, one locking element 13 on being rotated uninterruptedly in a clockwise or anti-clockwise direction will, after passing through a number of degrees of rotation, pick up the adjacent inner locking element 13 which, in turn, picks up the locking element 13 within it whereby the said locking elements 13 may all be caused to rotate in unison if desired. Similarly the lug 25 on the flanged casing 20 after said casing passing through a number of degrees of rotation registers with the lug 27 on the outer collar or locking element 13 and causes said outer collar to rotate in unison therewith.

55 60 65 70 75 Each of the locking elements 13 is provided with a cut-out 28 on the edge adjacent the disc or circular plate 11 and through which the rib 7

and teeth 8 on the base plate 6 are adapted to move when cut-outs 28 of all the locking elements 13 and the cut-out 24 on the flange 21 of the casing 20 are in alignment.

75 80 85 90 95 With the elements 13 and casing 20 in this position the base plate 6 is adapted to be moved thereby permitting unlocking means connected with said base plate 6 to be operated and, in one embodiment of the invention, I will refer to its use in conjunction with the door of a safe and, as illustrated in the accompanying drawing, the locking mechanism being disposed between the outer casing 29 of the safe and the inner lining 30 thereof.

95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

safe, the said latter projections 49 being concentrically arranged in the manner of a clock dial, such sets of projections 48 and 49 permitting the lock to be operated by sense of touch in the 5 darkness.

To operate the lock the user, being aware of the combination, imparts firstly rotation to the control dial 34 whereby all the locking elements 13 may rotate in one direction to ensure that the 10 lock is ready for adjustment.

As the projections 49 on the casing 29 correspond with predetermined settings for each locking element 13, the operator rotates the dial 34 to effect the setting preferably of the innermost 15 locking element 13 to adjust the cut-out 28 therein with the circular plate 11 to register or coincide with the radial slot 14 in alignment with the rib 7 and teeth 8 of the circular plate.

The control dial 34 is then rotated in an opposite direction to adjust the next adjacent locking element 13 to bring its recess 28 into alignment with the previously adjusted element 13 to be in alignment with the said teeth 8.

Each locking element 13 is adjusted by continuous rotation in an anti-clockwise and clockwise direction by the control dial 34, the engagement of the respective lugs 25 and 27 between the casing 20 and the locking elements 13 effecting the rotation.

When the casing 20 and all the locking elements 13 have the respective cut-outs 24 and 28 in alignment with the teeth 8 the operating knob 36 is depressed to disengage the head 32 of the extension shaft 33 from the slot 31 in the flanged casing 20 and thereby permit the unlocking rack 41 to be operated by the continued rotation of the control dial 34 without displacing the locking elements from their position.

In another embodiment of the invention when the lock is attached to hand or cash bags or portmanteaux or the like, the catch on one flap or side of the article may be in the form of a recess to engage with a bolt or projection connected to the disc or circular plate 11 adjacent the base plate 6, which base plate 6 becomes the fixed member and the lock and associated parts the lateral moving member so that when all the locking elements 13 have their respective cut-outs 28 in alignment with the teeth 8 of the base plate 6 the flanged casing 20 may be moved laterally whereby the said locking elements 13 move laterally along the rib 7 and carry with them the before-mentioned bolt or projection.

In the above modification the invention is of neat and compact appearance, being substantially small in comparison with the size of the types of locks at present employed utilizing the combination principles so that the lock provides for efficient application to cash bags or business bags in which valuable papers may be carried.

In applying the lock to safes and doors a further handle may be employed if necessary other than the operating knob 36, which handle would be operatively connected with the lock or catch whereby, after the control dial had been set to adjust the locking mechanism to permit same to move, the handle could then be adjusted to effect the displacement of the catch or bolt to open the door or safe.

If desired the invention may be utilized in conjunction with the switching mechanism of radio sets or the like to prevent independent adjustment for the condensers and eliminate unauthorized use of the set.

What I claim as my invention and desire to secure by Letters Patent is:—

1. An improved combination lock characterized by a plurality of circular collars concentrically and rotatably arranged in grooves with- 5 in a flanged casing, the said collars and casing having cut-outs adapted to be brought into alignment to release means for actuating unlocking mechanism.

2. An improved combination lock characterized by a plurality of locking elements concentrically and revolvably disposed between grooved plates the said elements being adapted to be independently positioned to bring cut-outs formed 15 therein into alignment and release associated means for unlocking an article to which the lock is attached.

3. An improved combination lock, comprising a plurality of concentric locking elements rotatably disposed between grooved plates located 20 within a flanged casing, lugs projecting exteriorly and interiorly from each element to impart rotation from one element to the adjacent inner element, the outer element being rotated by a 25 lug projecting interiorly from the wall of the flanged casing rotatably connected to one of the grooved plates, said casing on being rotated in sequence in an anti-clockwise and clockwise direction to predetermined settings effects the positioning of the locking elements to bring said cut-outs formed therein in alignment to permit an independent section completing the concentric grooves in one of said plates to be displaced for the purpose of actuating unlocking means. 30

4. An improved combination lock characterized by a casing adapted to be rotated in a clockwise and anti-clockwise direction to effect a predetermined setting of locking elements concentrically and revolvably arranged within said casing and thereby permit means associated with said elements to be moved by a further manipulation of the casing whereby an article to which the lock is attached may be opened. 40

5. An improved combination lock comprising a 45 plurality of locking elements concentrically and rotatably disposed within a casing slidably mounted in relation to a base plate, a radial rib on said base plate, teeth formed in said rib and adapted to seat in the locked position between the locking elements, cut-outs formed in the locking elements each of which elements is adapted to be independently set to bring all the cut-outs into registration and alignment with the teeth to permit the said elements to be displaced from the 50 locked position to effect the unlocking of a bolt or catch and thereby open an article to which the lock is attached.

6. An improved combination lock according to 55 claim 3 and wherein the rotatable casing has an upraised indicator or marking adapted to be set in relation to fixed upraised indicators surrounding the casing to permit the lock to be manipulated by sense of touch.

7. An improved combination lock, comprising 65 a plurality of cylindrical locking elements concentrically and rotatably arranged in grooves, the locking elements being located within a flanged casing, said elements and casing having cut-outs adapted to be brought into alignment to release 70 means for actuating unlocking mechanism.

8. An improved combination lock, comprising a plurality of cylindrical locking elements concentrically and revolvably disposed between grooved plates, said elements being adapted to 75

- be independently positioned to bring said cut-outs formed therein into alignment and permit the release of associated means for unlocking an article to which the lock is attached.
5. 9. An improved combination lock, comprising a plurality of locking elements concentrically and revolvably arranged in grooved plates located within a casing, each of the locking elements having a cut-out or recess adapted to be brought 10 into alignment with an independent movable section forming portion of one of the grooved plates to permit said section to be displaced in an outward direction for actuating means to unlock the article to which the lock is attached.
15. 10. An improved combination lock, comprising a plurality of locking elements concentrically and revolvably arranged in grooved plates located within a casing, each of the locking elements having a cut-out or recess adapted to be brought 20 into alignment with an independent movable section forming portion of one of the grooved plates to permit the movable section to be displaced in an outward direction, such displacement preventing said casing and locking elements being rotated while said section actuates means to unlock the article to which the lock is attached.
30. 11. An improved combination lock, comprising a plurality of locking elements concentrically and revolvably located within a casing, the manipulation of said casing effecting the operation of the locking elements to allow the release of a catch or bolt associated with said lock to effect the opening of an article to which the lock is attached.
35. 12. An improved combination lock, comprising a plurality of concentric locking elements revolvably mounted in and associated with a rotatable casing, a slideable bolt or plate in operable conjunction with said locking elements, means associated with said elements whereby rotational impulses imparted to the outer locking element are transmitted to the inner elements according to the direction of rotation imparted to the casing whereby rotating the casing in a clockwise and 40 anti-clockwise direction the locking elements are set to a predetermined release position in accordance with the casing setting to permit said slideable bolt or plate to be operated and displaced from the locked position for the purpose of 45 opening the article to which the lock is attached.
50. 13. An improved combination lock, comprising a plurality of locking elements concentrically and revolvably arranged in grooved plates located within a casing detachably connected with the extension shaft of a combined control dial and operating knob, the dial effecting the rotation of the casing in an anti-clockwise and clockwise direction, in sequence, to effect the position of each locking element to release a base plate at 55 which time a depression of the operating knob permits the rotation of said extension shaft and control dial independently of said casing to dis-
- place said base plate from its locked position and simultaneously operate unlocking mechanism to open the article to which the lock is attached.
14. An improved combination lock comprising a plurality of independent locking elements concentrically and rotatably arranged between grooved plates, a cut-out in each element, a rotatable flanged casing detachably connected to one of the said grooved plates and completely housing the locking elements, a projecting lug 10 on the inner wall of said casing and adapted when rotated through a predetermined number of degrees to register with a lug projecting exteriorly from the outer locking element, the former lug effecting the rotation of said outer element, a lug projecting interiorly from the outer locking element and adapted when rotated through a predetermined number of degrees to register with a lug projecting exteriorly from the adjacent inner locking element to effect the rotation of said inner element, the said casing when rotated in an anti-clockwise and clockwise direction effecting by means of the said lugs the alignment of all the cut-outs in said elements and a cut-out in the flange of the casing with teeth disposed on a slideable base plate forming portion of the grooves of the plate adjacent the flange of the casing, to permit said teeth and base plate to be displaced outwardly to actuate 20 unlocking means to open an article to which the lock is attached.
15. An improved combination lock comprising a plurality of locking elements concentrically and revolvably arranged in grooved plates located within a casing adapted to be rotated by an extension shaft detachably connected with said casing, the said shaft having a control dial slideable thereon and a spring-controlled operating knob mounted thereto, the operating knob disengaging the shaft from said casing and engaging said shaft with a pinion whereby on the rotation of the knob and control dial unlocking means are adapted to be actuated when the locking elements within the casing are in a predetermined position.
25. 16. An improved combination lock comprising a plurality of locking elements concentrically and revolvably arranged between grooved plates located within a casing adapted to be rotated by an extension shaft detachably connected thereto, the said shaft having a control dial slideable 30 thereon and a spring-controlled operating knob mounted thereto, the dial effecting the rotation of said casing to position the locking elements in an unlocked position in relation to a slideable base plate, the operating knob disengaging the shaft from said casing and engaging said shaft with a pinion having means associated therewith for unlocking purposes, said means moving in unison with the said base plate when the locking elements within the casing are in an unlocked 35 position.
40. 45. 50. 55. 60.

FRED BURNS.
